METHOD AND MEANS FOR ABRADING LENSES

Carl E. Anderson, Hackensack, N. J., assignor to Bausch & Lomb Optical Company, Rochester, N. Y., a corporation of New York

Application March 7, 1930, Serial No. 433,934
Renewed May 14, 1937

11 Claims. (Cl. 51—131)

This invention relates to the lens grinding and polishing art wherein an abrading tool or lap is moved over the surface of a lens to grind or polish it.

5 In the machines which characterize the prior art a great deal of difficulty has been experienced because the surface of the abrading tool or lap does not wear away uniformly throughout its area. This is due, in part, to the difference in 10 area between the work and the abrading tool, partly to the difference in speed between the work and the tool and partly to the location or position of the abrading surface on the surface of the work.

15 One of the objects of this invention is to provide a method and means for abrading lenses whereby the abrading tool will be worn away substantially uniformly throughout its entire area. Another object is to provide a method and means 20 for abrading lenses wherein the abrading tool and the work are moved relatively to each other so that at periodic intervals the entire area of the work is brought cumulatively into contact with substantially the entire area of the abrading tool 25 so that the tool is worn away uniformly over its surface. Other objects and advantages reside in certain novel features of construction, arrangement and combination of parts and in my improved method as will hereinafter be more fully 30 described and pointed out in the appended claims.

Referring to the drawing:

Fig. 1 shows a sectional view of an apparatus embodying my invention.

Fig. 2 is a schematic diagram illustrating the 35 overlapping relation between the tool and the lens.

One embodiment of my invention is illustrated in the drawing wherein L indicates a lens blank which is to be operated upon. The blank L is 40 mounted, by any suitable means, on a block or chuck 10 which is carried by spindle 11 and adapted to be rotated through the application of suitable power to the pulley 12. A suitable abrading tool or lap 13 is carried by spindle 14 so that it 45 may be rotated or driven by a belt or other means through the pulley 15.

The diameter of the abrading tool 13 is substantially equal to the diameter of the lens L so 50 that the area of the abrading surface is substantially the same as the area of the surface of the lens to be ground or polished. The spindle 14 is inclined, as shown in Fig. 1, so that the tool 13 overlies the lens L with the edge of the tool positioned substantially at the center of the lens and

with the axis of the spindle 14 positioned substantially at the edge of the lens L.

In operation, the lens L is rotated in one direction and the tool 13 is rotated in the opposite direction, the rotational speeds of the lens and tool being substantially equal. The overlapping of the tool and lens is shown diagrammatically in Fig. 2 wherein the lens and the abrading tool are represented, respectively, by L' and 13' and the two arrows show the directions of rotation of 10 the lens and tool. In actual practice, the tool 13 is positioned so that its edge is slightly over the center of the lens L to prevent the formation of a central high spot on the lens. The spindle 14 could also be oscillated a slight amount so that 15 the tool would pass slightly over the center of the lens to prevent the formation of a central high spot on the surface of the lens.

Since the edge of the tool is positioned substantially at the center of the lens and since the tool 20 and the lens have substantially the same diameters and rotational speeds, the abrasive action will be substantially uniform over the entire surface of the tool. At a given instant, the contacting area of the lens is substantially equal to 25 the contacting area of the tool so that at the end of a complete revolution the entire area of the tool will have contacted, cumulatively, with a substantially equal area on the surface of the lens. Hence the abrading action or wearing away 30 of the tool will be substantially uniform over its entire area so that the tool may be used for grinding a large number of lenses without necessitating frequent truing-up of the tool as was required under prior art methods. My improved 35 method and means may be applied, equally well, to either the grinding or polishing of lenses and it is to be understood that the term "abrading" refers to both grinding and polishing operations.

From the foregoing it will be apparent that I 40 am able to attain the objects of my invention and provide improved method and means for abrading lenses wherein the abrading tool will be worn away in a substantially uniform manner over its entire area. Various modifications can 45 obviously be made by persons skilled in the art and it is to be understood that such modifications are to be included within the spirit and scope of my invention as defined in the appended claims.

I claim:

1. A method of abrading lenses which comprises rotating an abrading tool in contact with a lens having substantially the same diameter and area as the tool, holding said tool with its 55

edge positioned substantially at the center of said lens and in contact therewith and rotating said lens at substantially the same speed of rotation as said tool but in an opposite direction.

5. 2. Lens abrading apparatus comprising means for rotating a lens and means for rotating an abrading tool at substantially the same speed as the lens but in the opposite direction, the diameter and area of said tool being substantially the 10 same as the diameter and area of the lens, the axis of rotation of said tool being located substantially at the edge of said lens.

15. 3. A method of abrading lenses which comprises placing an abrading tool in contact with a lens of the same area and diameter so that the tool projects beyond the edge of the lens, and rotating the tool and the lens so that the linear velocity of any point on the lens plus the linear velocity of the point on the tool which contacts 20 with said point on the lens will be a substantially constant sum.

25. 4. Lens abrading apparatus comprising a vertical spindle carrying a block which supports a lens blank, a second spindle mounted above said block, the axis of said second spindle being inclined to the vertical and passing substantially through the edge of the lens blank, a grinding tool rigidly carried on said second spindle, said tool having substantially the same area and 30 diameter as the lens blank whereby said tool contacts with said blank in overlapping relation and means for rotating said tool and blank at the same speeds but in opposite directions.

35. 5. A method of abrading a lens having a substantially spherical surface which comprises placing in contact with said surface an abrading tool having a spherical abrading surface which has substantially the same diameter and area as the surface on the lens, holding said tool with its center positioned substantially at the edge of said lens and rotating said lens and tool at substantially the same speeds but in opposite directions.

45. 6. A method of abrading lenses which comprises rotating an abrading tool in contact with a lens having substantially the same diameter as the abrading surface of the tool, holding said tool with its abrading surface contacting said lens and with the central part of the abrading 50 surface positioned substantially at the edge of the lens, and rotating said lens at the same speed of rotation as the tool but in an opposite direction.

7. A method of abrading lenses which com-

prises placing a circular abrading tool having a continuous surface in contact with a circular lens having a surface whose area and diameter are substantially the same as the area and diameter of the surface of the tool, holding said tool with 5 its center substantially at the periphery of said lens and rotating said lens and tool in opposite directions but at the same speeds so that the surface speed of any point on the lens plus the surface speed of the point on the tool which contacts with said point on the lens will be a substantially constant sum.

8. Lens grinding means comprising a spindle carrying a block for supporting a lens, a second spindle mounted above the first spindle and in 15 angular relation thereto, an abrading tool fixedly secured to said spindle, said tool having a substantially continuous spherical surface whose area and diameter are substantially the same as the area and diameter of the lens, said tool being positioned in contact with the lens with its edge substantially at the center of the lens and means for rotating said spindles at the same 20 speeds but in opposite directions.

9. The method of abrading lenses which comprises placing an abrading tool in contact with a lens of substantially the same area and diameter so that the tool projects beyond the edge of the lens, rotating said lens, and rotating said 25 tool at substantially the same speed as said lens 30 about an axis adjacent the edge of said lens so as to bring substantially the entire area of the lens cumulatively into contact with substantially the entire area of the tool once for each rotation of the lens and tool whereby the wear on the 35 tool will be uniform and the form of the original surface thereon will be preserved.

10. A method of abrading lenses which comprises rotating an abrading tool in contact with a lens having substantially the same diameter and 40 area as said tool, rotating said lens at substantially the same speed of rotation as said tool and oscillating said tool during rotation.

11. A method of abrading lenses which comprises placing a lens element in contact with a tool element of substantially the same area and diameter as said lens element so that the center of the lens element is closely adjacent the edge of said tool element, rotating said elements at substantially the same speed of rotation and oscillating one of said elements so that the edge of the tool element moves back and forth across the center of the lens element.
